UNITED STATES PATENT OFFICE.

ADAM BOOMERSHINE, OF DAYTON, OHIO.

DISPENSING APPARATUS.

Application filed July 26, 1922. Serial No. 577,623.

To all whom it may concern:

Be it known that I, ADAM BOOMERSHINE, a citizen of the United States, residing at Dayton, in the county of Montgomery and 5 State of Ohio, have invented certain new and useful Improvements in Dispensing Apparatus, of which the following is a specification.

This invention relates to improvements 10 in dispensing apparatus, having a plurality of compartments for the commodity to be dispensed, the apparatus shown in the drawing having been especially designed for dispensing ice cream cakes, although the construction is equally applicable for the purpose of dispensing other commodities.

One of the objects of the invention is to provide a simple and effective arrangement 20 of ejectors whereby the articles to be dispensed will be completely exhausted from one compartment and then fed from the next succeeding compartment, or the next compartment containing articles of commodity; the arrangement being such that 25 an intervening empty compartment may exist without interfering with the proper ejection, one at a time, of all of the articles in the machine.

A further object of the invention is to provide an ice chamber and commodity holders 30 which may be readily removed for cleaning or repairs; a further object in this connection being to so dispose the parts that the ejectors and tripping devices for same will be readily accessible for inspection and 35 repairs when the ice chamber and holders are removed.

A further object of the invention is to provide a dispensing apparatus which will be 40 simple in construction, effective in operation and economical in manufacture.

In the accompanying drawings:

Fig. 1 is a side elevation with the near side of the outer casing removed.

Fig. 2 is a section on the line 2—2 of 45 Fig. 6.

Fig. 3 is a perspective view of one of the ejectors and its operating arm.

Fig. 4 is a perspective view of one of the 50 trip fingers for the ejector arms.

Fig. 5 is a section on the line 5—5 of 55 Fig. 6.

Fig. 6 is a section of the line 6—6 of 60 Fig. 5.

Fig. 7 is a plan view of two of the trip 65 arms in assembled relation.

Fig. 8 is a section on the line 8—8 of 70 Fig. 9.

Fig. 9 is a side view of one of the commodity holders. 75

Fig. 10 is a section on the line 10—10 of 80 Fig. 9.

Referring to the drawings, a casing is 85 provided consisting of an outer wall 1 and an inner wall 2 of sheet metal with insulating material 3, such as ground cork, packed between the walls. This casing forms the bottom, side and end walls of a compartment which receives an ice chamber and the commodity compartments or holders and is 90 supported from a base 4 by legs 5. The top of this casing is closed by cover 1^a formed in a manner similar to the casing in that it has double sheet metal walls filled with 95 cork or similar material. 75

An open-top ice chamber 6, preferably of sheet metal is fitted to the walls 2 and has handles 7 by which it may be readily removed. This ice chamber is shaped to surround an open-top commodity chamber 8 80 consisting of side and end walls of sheet metal suitably secured to the bottom wall 2. The commodity packages 9 are placed in suitable holders 10, the lower end of each of which has front and rear openings 11 to 85 permit the ejection of the commodity packages and also preferably vertical side slots 12, to facilitate the placing of the packages therein, and these holders filled with the packages are placed between vertical, narrow 90 guides 8^a projecting from the walls 8 of the commodity chamber.

The main outer casing has extending from front to rear a chamber, the rear part 13 of which forms a housing for certain of the 95 operating parts, the forward portion thereof a discharge opening 14 for the commodity receptacles, and the intermediate portion thereof a receiver for the lower-most ends of the commodity holders and a place to 100 house the guideways for the ejectors. These guideways are indicated at 16 and are preferably constructed of sheet metal. Slidably mounted in the guideways are ejectors 17 (see Fig. 3 for detail) consisting of 105 a top portion 17^a, two sides 17^b and a forward end 17^c of lesser depth than the sides. Each ejector has an operating arm 18, the forward end of which is pivotally mounted on a pin 19 carried by the side walls of the 110 corresponding ejector and the rear end of which is bent to a hook-shaped form, as

indicated at 18'. All of the operating arms, excepting the one of the first commodity compartment, are normally held in inoperative position by a device associated with a preceding compartment, so that when the packages in any one compartment are exhausted the operating arm of the next succeeding compartment is automatically permitted to engage itself with the operating mechanism to be later described. Each of the guide-ways except the first in the series has a depressed channel 20 and pivotally-mounted in the side walls of each channel is a trip-arm 21, the arm having lateral trunnions 22 near its rear end for this purpose. The rear end of each arm has a notch 23, and also a laterally extending finger 24 having an upwardly extending projection 25. The extreme outer end of the finger 24 lies beneath that portion of the succeeding trip arm indicated at 23^a so as to sustain that arm and prevent it from dropping in the event that its companion compartment should be empty, which insures against the commodity being fed from more than one compartment at a time. The weight of the packages is upon the forward end of the trip arm so that its rear end is tilted to a position to cause its projection to engage the underside of the next succeeding operation arm 18, the notch 23 of that arm being for the purpose of accommodating the projection. As the last package of any one compartment, except of course the last in the series, is fed from the compartment, the trip-arm of that compartment is permitted to swing and thus permit the rear end of the operating arm of the next succeeding compartment to drop and cause its hook-shaped end to engage a rod 26 carried at the upper end of arms 27, the lower ends of which are fixed to a rock shaft 28. One end of the shaft 28 has a crank-arm 29, the upper end of which has a pin 30 projecting into a slotted opening 31 of a link 32, the other end of the link being pivoted to one arm of a bell crank lever 33. The other end of the bell crank lever is pivotally connected by a link 34 with a lever 35, having its rear end pivoted at 36 and normally held in retracted or inoperative position by a spring 36'. This lever is operated by a plunger 37 mounted to slide in a vertical direction in a channel 38 in the wall of the outer casing, and pivotally connected to the lever 35 by a link 39; the plunger having a finger piece 37' to be readily grasped by the operator. The operating devices are normally locked and designed to be unlocked by a coin inserted in the inclined slotted opening 40. A locking lever has one arm 41 thereof normally standing in the path of the coin, a flat spring 41' normally holding the arm in this position. The other arm 42 of the lever

has a lateral projection 43 normally standing in the path of movement of a finger 44 projecting downwardly from the forward end of the lever 35. When a coin is deposited, it comes to rest against the arm 41 of the locking lever just beneath the plunger 37. When the plunger is depressed, it comes in contact with the coin and swings the locking lever, causing the projection 43 thereof to be moved out of the path of the finger 44. The slotted opening 31 in the link 32 is to permit of a preliminary movement of the parts as the plunger is depressed and until the lever 35 is unlocked. The coin then slides down the channel 38 into the coin box 45. The plunger is of sufficient length so that when depressed its upper end will extend across the coin slot and thereby prevent the insertion of a coin until the plunger returns to normal position.

Arranged in the discharge opening in front of each compartment is a pair of hinged doors or valves 46 which swing outwardly to permit the discharge of the articles and then swing inwardly to keep the discharge opening closed against outside air.

Upon each operation of the apparatus a package is dispensed, first from the first occupied compartment in the series until exhausted and then from a succeeding occupied compartment. When the packages in the first occupied compartment are exhausted the trip arm of that compartment moves about its pivotal point, due to the weight thereon of the operating arm of the next succeeding compartment, and permits that operating arm to drop and becomes engaged with the rod 26. In the event that an intermediate compartment is empty, its trip will be sustained by the trip arm of the preceding filled or partly filled compartment and thus sustain the operating arm of the next succeeding filled compartment, dropping simultaneously with the preceding trip arm to thereby release the next succeeding operating arm. By this arrangement intermediate compartments may be empty, but the apparatus will continue to dispense packages so long as any packages remain in the machine, so that careless filling of the compartments will not interfere with the proper dispensing of the commodity.

It will be noted that the ice compartment together with the commodity holders may be readily removed for inspection and repairs, such removal also affording access to the ejectors and associated parts.

Having thus described my invention, I claim:

1. In a dispensing apparatus, a plurality of commodity compartments, an ejector for each compartment, commodity controlled means for holding all of the ejectors ex-

cepting for the compartment being dispensed out of operation and for throwing an ejector of a succeeding occupied compartment immediately into operation when the 5 commodity in a preceding occupied compartment is exhausted.

2. In a dispensing apparatus, a plurality of commodity compartments, an ejector for each compartment, commodity controlled 10 means for holding the ejector of a succeeding compartment out of operation until the commodity of the preceding compartment is exhausted, and additional interlocking means for holding succeeding ejectors out 15 of operation until the commodity of the first occupied compartment is exhausted so arranged as to release the ejector of the next succeeding occupied compartment immediately upon the dispensing of the last 20 article in the preceding occupied compartment.

3. In a dispensing apparatus, a series of commodity compartments from which packages of commodity are adapted to be dispensed in successive order, a normally inoperative ejector for each compartment after the first, commodity controlled means 25 for holding said ejectors out of operation until the commodity of a preceding compartment is exhausted, and means for permitting all ejectors to be thrown into operation between the last compartment dispensed from and the next occupied compartment immediately upon the ejection of 30 the last commodity article from said first-mentioned compartment.

4. In a dispensing apparatus, a plurality of compartments for commodity packages, an ejector for each compartment, means controlled 40 by the packages in one occupied compartment for preventing the operation of the ejectors in succeeding compartments whether empty or occupied, said means permitting the operation of the ejector of the 45 next succeeding occupied compartment when the packages in the first-mentioned compartment are exhausted regardless of intervening unoccupied compartments.

5. In a dispensing apparatus, a plurality 50 of commodity compartments, a separate ejector for each compartment, a common operating device for said ejectors, means for connecting each of said ejectors with said operating device, a trip arm controlled by 55 the commodity packages in a compartment for holding the ejector in a succeeding compartment disconnected from said operating device, and interlocking connections to pre-

vent the operation of the trip arm of any unoccupied compartment until the preceding 60 occupied compartment is emptied.

6. In a dispensing apparatus, a plurality of commodity compartments, an ejector for each compartment, an actuating device for each ejector, an operating device for said 65 actuating devices, commodity controlled trips each arranged to release an actuating device of a succeeding compartment when the commodities of the preceding compartment are exhausted, and interlocking connections 70 to prevent the release of the actuating devices of any unoccupied compartment, independent of its particular location, until the commodities of the preceding occupied compartments are emptied. 75

7. In a dispensing apparatus, a plurality of commodity compartments, an ejector for each compartment, a movable operating arm carried by each ejector, an operating device 80 for said ejectors, and means controlled by the commodity articles for holding said arms out of engagement with said operating device and permitting the arm of a succeeding occupied compartment to become engaged with said device when the articles of 85 any one compartment are exhausted.

8. In a dispensing apparatus, a plurality of commodity compartments, an ejector for each compartment, a movable operating arm carried by each ejector, a movable trip arm 90 associated with the majority of said compartments, and a main operating device, each trip arm being controlled by the commodity in its compartment to hold the next succeeding operating arm out of operative 95 position and to permit said operating arm to engage with said operating device when the commodity articles are exhausted.

9. In a dispensing apparatus, a plurality of commodity compartments, a main operating device comprising an oscillatory rod extending throughout the breadth of said compartments, an ejector for each compartment, an operating arm pivoted to each ejector having a hook-shaped end to engage with said rod, and a commodity controlled 100 trip arm associated with the majority of compartments arranged to hold the operating arm of the next succeeding compartment in inoperative position when its compartment is occupied and permit said operating arm to engage said rod when its compartment is exhausted. 105

In testimony whereof, I have hereunto set my hand this 20th day of July, 1922.

ADAM BOOMERSHINE.
